UNITED STATES PATENT OFFICE.

ALBERT O. ROBERTS, OF NEW KENSINGTON, PENNSYLVANIA.

INTERNAL-COMBUSTION ENGINE.

Application filed April 12, 1922. Serial No. 551,808.

To all whom it may concern:

Be it known that I, ALBERT O. ROBERTS, a citizen of the United States of America, residing at New Kensington, in the county of Westmoreland and State of Pennsylvania, have invented new and useful Improvements in Internal-Combustion Engines, of which the following is a specification.

The object of my present invention is 10 the provision of an internal combustion engine having the capacity of converting a large portion of the heat of combustion into mechanical energy with a view to attaining high efficiency.

15 To the attainment of the foregoing, the invention consists in the improvement as hereinafter described and definitely claimed.

In the accompanying drawings, forming part hereof:

20 Figure 1 is a longitudinal central section, part in elevation, illustrating the best practical embodiment of my invention that I have as yet devised.

25 Figure 2 is an enlarged, detail, vertical section of a portion of the same.

Figure 3 is a horizontal section taken in the plane indicated by the line 3—3 of Figure 2, looking downwardly.

30 Figure 4 is a detail horizontal section taken in the plane indicated by the line 4—4 of Figure 1, looking downwardly.

Similar numerals of reference designate corresponding parts in all of the views of the drawings.

35 The main cylinder 1 of my novel engine is provided at opposite sides thereof with annular valve seats 3 and 4, the openings in the said valve seats being in communication with the atmosphere, and the opening in

40 the valve seat 3 being for the outward passage of products of combustion while the opening in the valve seat 4 is for the admission of atmospheric air. The exhaust valve opposed to the seat 3 is numbered 5 and

45 the inlet valve opposed to the seat 4 is numbered 6. At 2 is the head of the cylinder 1.

1. The central bore 7 in said head 2 is smaller than the bore of the cylinder 1 in about the proportion illustrated, and is provided with appropriate packing rings 8 or other packing means compatible with the purpose of my invention.

Movable rectilinearly in the main cylinder 1 is a piston 9 at the outer end of which is a collar flange 10 in which are aper-

tures or ports 11. The said flange 10 is exteriorly threaded at its upper end for the engagement of a coupling nut 12 through the medium of which a live cylinder 13 is coupled to the piston 9 in such manner as to assure rectilinear movement of the live cylinder 13 with the piston 9 while permitting of movement of the live cylinder 13 about its axis in the collar flange 10. It will be noticed in this connection that the cylinder 13 is provided with ports 14 arranged to be moved into and out of registration with the ports 11, and that the said cylinder 13 is also provided with a circumferential flange 15, interposed between the flange on the nut 12 and the end of the cylinder 13. At its outer end the cylinder 13 is provided with an interior saddle 16, connected to it through the medium of screws 17.

75 Spaced from the main cylinder 1 and fixedly connected therewith as shown is a head block 18 from which extends an intake manifold 19, designed to be connected with a carburetor or other source of explosive mixture supply. The said head block 18 is provided with a tubular interiorly threaded projection 20 in which is disposed the correspondingly threaded end portion of the tubular piston rod 21 of the piston 22. The 80 said piston 22 is disposed in the live cylinder 13, is appropriately packed at 23 and is provided with a port 24 for the supply of explosive mixture to the cylinder 13 and is also provided with ignition means preferably in the form of a spark plug 25. The 85 port 24 is controlled by a valve 26, the stem 27 of which is extended through the tubular piston rod 21 as illustrated.

At 28, 29 are stationary guides, and at 29 90 is an operating arm.

The main cylinder 1 is connected to a crank casing 30 in the manner illustrated in Figure 1 or in any other appropriate manner, and the main piston 9 is provided with a wrist pin 31, designed to be connected in the conventional manner with the crank shaft of the engine.

100 It will be manifest from the foregoing that by turning the live cylinder 13 about its axis the ports 11 in the collar flange 10 may be opened and closed.

105 The saddle 16 is arranged, Figures 2 and 3, to travel on the guides 28 which guides are carried by the sleeve 32 that surrounds the 110

stationary tubular piston rod 21, and is interposed between the piston 22 and projection 20.

The operating arm 29 on the said sleeve 5 32 is actuated by a cam 33, arranged as illustrated, in Figures 1 and 4.

The operation of my improvement will be clearly understood when it is stated that on the intake stroke and with the piston at the 10 top of its stroke the ports 11 are closed and the valves 6 and 26 are opened. As the piston recedes the cylinder 13 is charged with explosive mixture from the intake manifold, and the space between the cylinders 1 and 15 13 is filled with air. The ports 11 remain closed incident to the compression stroke until they approach the top when they will be opened in the manner hereinafter described. Very little mixture of gases will 20 take place between the opening of the said ports 11 and the time of explosion inasmuch as at that time both gas and air are compressed to the same extent. Following the 25 ignition a portion of the burning gas will rush into the compressed air in the space between the cylinders 1 and 13, and hence the air will serve as a cushion to absorb the shock, and becoming heated will keep the 30 pressure practically constant through about two-thirds of the power stroke. The ports 35 11 remain open until the end of the exhaust stroke is reached so that the products of combustion from the cylinder 13 and the cylinder 1 can escape through the apertured valve seat 3, the valve 5 being at that time open.

It will be manifest from the foregoing that in effect the cylinder 13 is surrounded by an air space in which atmospheric air 40 is compressed simultaneously with the compression of the explosive mixture in the cylinder 13. The excess heat given off by the burning gas operates to heat the said air, and the expansion of the air assists in 45 the movement of the main piston 9.

Having described my invention, what I

claim and desire to secure by Letters Patent, is:—

1. An internal combustion engine, comprising a main cylinder having a port for the entry of air and also having a port for the discharge of products of combustion, valves to control said ports, a piston arranged to work in said cylinder, a cylinder arranged in and spaced from the main cylinder, and movable rectilinearly with the piston and about its axis independently of the piston, the latter to control communication between its interior and the space between it and the main cylinder, means closing the second-named cylinder, means to supply the second-named cylinder with explosive mixture; said means including a tube and a valve controlling communication between said tube and the interior of the second-named cylinder, a sleeve surrounding said tube, an operating arm on said sleeve a saddle in the second-named cylinder, and guide means on said sleeve and engaging said saddle. 50 55 60 65 70

2. In an internal combustion engine, the combination of a main cylinder, a head connected therewith and having an intake manifold, a tube connected with said head, a piston connected with said tube and having a port, a valve to control said port and having a stem extending through said tube, a piston movable in the main cylinder, a cylinder arranged in and spaced from the main cylinder and containing and movable relatively to the first-named piston and movable rectilinearly with and about its axis independently of the second-named piston, the latter to control communication between its interior and the space between it and the main cylinder, a saddle in the second-named cylinder, a sleeve surrounding the tube and provided with an operating arm, and guide means on the sleeve and engaging said saddle. 75 80 85 90 95

In testimony whereof I affix my signature.

ALBERT O. ROBERTS.
